[57] ABSTRACT

A loudspeaker system having an electroacoustical transducer and a sound-propagating member with at least a principal sound-emitting axis. The sound director is movable to swing the axis through an angle to its normal position and thereby change the sound distribution accordingly. Stereophonic effects and changes in the quality of the tone (expression) are audible to the listener. The angle control may be effected independently of the electrical signal source or in dependence thereupon.

LOUDSPEAKER SYSTEM

FIELD OF THE INVENTION

The present invention relates to a loudspeaker and, more particularly, to loudspeaker systems designed to vary the quality of the audible signal.

BACKGROUND OF THE INVENTION

Stereophonic sound reproduction, generally, involves the conversion of an electrical signal representing a prerecorded audible signal, a radio-frequency transmission, a currently presented transmission (e.g. from a microphone) or the like, the loudspeakers each being formed with an electroacoustical transducer to convert the electrical signal into a vibratory output which, of course, constitutes a sound signal audible to the listener. For proper stereophonic effect, a clear demarcation must be maintained between the channels, i.e. the channels of pick-up, recording and amplification, the loudspeaker for the two or more channels must be properly spaced and oriented so that a balanced sound reaches the ear of the listener from distinct, separated sources.

Furthermore, aside from the above factors relative to stereophonic sound reproduction and enjoyment, it is found that loudspeakers are basically static members with limited audible depth of interest. As a result, the loudspeaker may lack expression, in certain instances, thereby rendering the sound produced unpleasant.

It may be noted, in passing, that it is also possible to provide mobile sound-generating station in which the entire loudspeaker is physically displaced, generally past the listening individual; this does not materially improve the expression or depth of audible sounds carried over such loudspeakers.

Thus, in spite of the considerable expense required in multi-speaker installations, the care expended to insure proper positioning of the sound-reproducing speakers, etc., the quality of the audited sound remains poor in many instances since the stereophonic recording or reproduction is often made from a mechanical recording the signals of which have been discriminated and separated to permit recording to two tracks with, for example, one being dominated by a high frequency, while the other is dominated by the low-frequency portion of the sound spectrum derived from an original recording.

OBJECTS OF THE INVENTION

It is, therefore, the principal object of the present invention to provide an improved loudspeaker system which is of low cost and yet can provide effects close to the stereophonic or, at any rate, improve the quality of the sound, depth, etc., directed at the listener.

Another object of the instant invention is to provide a single-speaker system capable of producing stereophonic and depth effects and avoiding the monotony usually prevalent in single-speaker arrangements.

Yet another object of this invention is to provide a system for applying "expression" to the sound emitted from a loudspeaker.

A further object of the instant invention is to provide an improved sound-propagating loudspeaker system capable of responding to signals dependent upon the electroacoustical signals and/or signals independent thereof.

SUMMARY OF THE INVENTION

These objects and others which will become apparent hereinafter are realized, in accordance with the present invention, in a loudspeaker system having an electroacoustical transducer and a sound-directing portion or member defining a sound-propagating axis, and means for displacing this axis, preferably to opposite sides thereof in a controlled manner and, generally, relative to the electroacoustical portion of the loudspeaker.

According to this invention, therefore, an actual sound-propagating axis is established which includes an angle with

the normal position of the axis and, desirable with another position of the axis so as to principally direct the sound, say, first to one side, then to the other side of the normal position of the axis.

When "displacement" of the sound-propagating axis of the loudspeaker is discussed herein, it is applicants' intention to refer to an angular displacement of the sound-propagating axis with respect to a pivot point or center of oscillation defined by the intersection of the displaced axes or the intersection of a displaced axis with the normal axis position. Displacement can involve swinging movement of the sound-directing member, i.e. wherein the axis oscillates back and forth in a single plane in a pendulum type of motion, or oscillatory motion about a pivot in a given plane or in one of a number of predetermined planes; also the motion may be gyratory or orbital. The displacement of the sound-directing member may also be effected, in accordance with this invention, such that the axis is swept about a closed path along any desired configuration, e.g. a circle, such that the path of the displaced axis defines a conical surface. Other displacement variations will, of course, be immediately apparent.

According to a feature of this invention, the sound-directing member is a cone diaphragm, the sound-propagation axis of which normally lies centrally of this cone and preferably coincides therewith. The cone may be composed of flexible material and may form part of the electroacoustical transducer, e.g. by virtue of a coil mounted upon the narrow part of the cone and cooperating with a stationary permanent magnet disposed adjacent the coil. Of course, the permanent magnet may be provided on the diaphragm-type cone, while the coil is fixed in place on the housing or yoke of the loudspeaker.

The sound-directing member may also be constituted by a horn or like member which is pivotal about an axis located at the intersection point of the normal sound-propagating axis and the offset or displaced axis and the movement of this sound-directing member can be effected by means of an electrical motor or the like with ease. It will be apparent, however, that in all cases the sound-directing member can be moved without displacing the entire assembly in the corresponding direction and that a system in which only the nonhousing portions are displaced is preferred.

The means displacing the sound-propagating axis of the loudspeaker may include electroacoustical, electrostatic or electric-motor means, depending upon the availability of such means only.

According to yet another feature of this invention, the oscillatory motion of the sound-propagating axis is effected periodically, e.g. by the use of an electric signal from a periodic source, or aperiodically with a random-signal generator or a signal depending upon one or more of the parameters of the signal feeding the voice coil of the unit.

The control of the swing of the axis may thus result from discrimination of amplitudes in the applied signals, i.e. the oscillation will occur only upon the development of high-amplitude signals. A frequency discrimination may also be used such that, for example, a loudspeaker will be rotated to the right or to the left with respect to its normal axis in response to a predominance of high-frequency and a predominance of low-frequency signals, respectively.

DESCRIPTION OF THE DRAWING

The above and other objects, features and advantages of the present invention will become more readily apparent from the following description, reference being made to the accompanying drawing in which:

FIG. 1 is an axial cross-sectional view through a loudspeaker embodying the present invention;

FIG. 2 is a similar cross-sectional view showing a modified embodiment thereof;

FIG. 2A is an enlarged detail view, somewhat exaggerated, showing a different positions of the sound-propagating element;

FIG. 3 is a cross section taken along the line III — III of FIG. 2;

FIG. 4 is an axial cross-sectional view through still another loudspeaker in accordance with this invention;

FIG. 4A is a cross section taken along the line IV—IV of FIG. 4;

FIG. 5 is a circuit diagram in which the oscillation of the sound-propagating axis of the unit is controlled in step with the amplitude of the acoustical signal;

FIG. 6 is a circuit diagram of a three-channel arrangement embodying the present invention and wherein the cone diaphragm may have gyratory motion;

FIG. 7 is a diagrammatic view of another loudspeaker embodying this invention; and

FIG. 8 is a circuit diagram, partly in block form, illustrating additional features of the invention.

SPECIFIC DESCRIPTION

From FIG. 1 it can be seen that a loudspeaker, in accordance with this invention, may be of dynamic type wherein a moving coil is energized to coact with a permanent magnet or a d.c. energized magnet.

The loudspeaker of FIG. 1 has a housing 1, 1a, the latter portion of which frustoconically diverges from the iron magnetically permeable yoke 1 whose center post 1b is coaxially surrounded by a flange 1d to which the cone 1a is affixed and 1b.

Along the interior of the flange 1d, there is provided a multiplicity of permanent magnets 2 or a single circularly polarized permanent magnet, the north and south poles of which are located along the inner and outer portions of the yoke respectively. The permanent magnet may cooperate with an oppositely polarized permanent magnet 2a mounted upon the post 1b and having north and south magnetic poles upon their inner and outer peripheries respectively. It will be apparent that the iron body 1 thus acts as a magnetic armature or core as represented by the dot-dash line 1e in FIG. 1 illustrating the lines of force spanning the gap between these magnets 2 and 2a so that the coil 4 carried upon a cylindrical portion of the diaphragm cone 3 closely surrounding the inner magnet 2a, can interact with the magnetic field by generating a magnetic field upon the passage of an electric current through the magnet coil and thereby allow the magnetic field to repel or attract and cause canting of the sound-producing coil 4.

As can be seen from FIG. 1, the outer periphery 3a of the cone 3 is provided with accordion pleats to lend flexibility to the diaphragm and permit canting between the dot-dash line positions shown in FIG. 1. The free end of the bellows is attached at 3b to the mouth 1f of the conical housing member 1a.

As can be seen from FIG. 2A, the cylindrical portion 3c of member 3 has a bottom wall 3d lying in a plane perpendicular to the post 1b in its normal position, and unitarily running into the cylindrical portion 3c formed with the coil 4. Since the wall member 3d is rigid with the post 1b along its inner periphery, the application of normal signal levels may result merely in an axial reciprocation of the diaphragm as represented by the arrows 3e. When, however, very high signals are produced, a canting of the diaphragm 3 occurs as shown in broken lines in FIG. 2A. In practice, it has been found that best results are attainable when the diaphragm is designed so as to be pivotal or swingable through an angle $\pm\theta$ of 30° to 40° as shown in FIG. 1.

FIGS. 2 and 3 show an embodiment of the present invention in which a rolling motion may be imparted to the principal sound-propagating axis so that oscillation is permitted in accordance with a resultant force and may, therefore, be random in nature. In this embodiment, a cone-shaped nonmovable member may be provided as is shown at 1a in FIG. 1 to hold the outer edge of the diaphragm cone 203 by its bellows-pleated periphery 203b. Here, however, the yoke 201 has a central post 201b cooperating with an axially positioned per-

manent magnet 202a closely surrounded by the axially extending cylindrical portion 203c of the conical member 203. The cylindrical portion 203c carries the voice or sound coil as previously noted. Surrounding the inner coil arrangement, there is provided a cylindrical wall 201d accommodating the cylindrical portion 203 with clearance.

Outwardly of this cylindrical wall 201d, I provide the massive body of the yoke with bores 251a, 252a, 253a and 254a receiving respective posts 201b' cooperating with coil sleeves 251-254.

The coil sleeves 251-254 are each connected with a corresponding point of diaphragm 203 as represented by the connecting rods 251a and 251b. Thus energization of coil 203c will cause the latter and the diaphragm 203 to oscillate in the usual manner, i.e. generally axially, along the path of sound propagation and, of course, in the direction in which such propagation is desired.

Signals applied to any of the coils 251-254 in unbalance will lead to a displacement of the diaphragm and, consequently, a swinging of the axis. For example let us assume that coils 251 and 252 are jointly energized while the remaining coils remain unenergized, the result will be an orbital swing of the axis. One coil, two coils, three coils and four coils may be energized in any succession to deflect the axis of sound propagation in the appropriate direction. Selective energization of the control coils permit selective pivotal motion of the cone and hence selective distribution of the angle and nature of the outwardly radiating sound. When the generating sound is to be directed preferentially to the left, coils 251 and 253 are energized to swing the axis toward them.

FIG. 5 shows a system which makes use of the amplitude of intensity of the sound-generating signal to cant, tilt or swing the diaphragm and, in general, to change the orientation of its major sound-propagating axis. The control circuit in FIG. 5, which may be connected to the coils 251-254 of FIG. 2 (these coils being represented at 51-54 in FIG. 5), comprises input terminals 7 to which an electric signal, e.g. derived from a radio receiver, a tape recorder, a microphone or the like, is connected; an amplifier 8 is fed by terminals 7. The amplified output may be a much lower frequency or the same frequency of amplified intensity in the frequency-response range of the speaker 300. The speaker 300 has a cone 303 which is pivotally mounted or is swingable relative to the yoke 401 as described in connection with FIG. 4. Each of the coils 51-54 has an armature 51' and 54' (FIG. 5) coupled with the sound emitting diaphragm 303. The signals appearing at the output terminals 8a of the amplifier 8 are applied to the sound coil 304 directly or via an output transformer; whereas the same terminals are bridged across a rectifying network 9, the output of which feeds the amplifier 10 a frequency-modulation unit with an internally generated carrier is connected to amplifier 10, the latter providing the modulating signal.

A phase circuit 12 (phase discriminator) breaks the modulated signal down into components associated with the respective amplitude levels and applies these signals to these respective coils 51-54.

The rectifying network 9 comprises a pair of oppositely poled rectifying diodes 9a, 9b, respectively in series with breakdown devices such as the Zener diodes 9c and 9d. The rest of the bridge is formed by a pair of resistors 9e and 9f so that only the signals remaining after clipping by the Zeners are amplified at 10 and passed along the circuit chain.

When the circuit of FIG. 7 is used in a microphone arrangement, for example, the microphone is connected to the terminals 7 and its acoustoelectrical transducer produces an electric output proportional to the sound input, the output being delivered to the coils 304 and the rectifying network 9.

Below a predetermined amplitude level established by the Zener diodes 9c and 9d, there is no output across the bridge 9a-9f and thus no modulation in the axial orientation of the sound-directing member of the loudspeaker. When, however, amplitude increases beyond the threshold value, the signal appearing across the bridge is amplified at 10, used as the modu-

lating wave at 11, is subjected to phase discrimination at 12 with the individual output being applied to the coils 51-54 to swing the axis in one direction or another and thereby reduce any raucous phenomenon and lend greater depth and "expression" to the sound.

FIGS. 4 and 4A show still another embodiment of my invention. This embodiment comprises a housing whose rigid frustoconical housing member 401a is provided with an axially extending rim 401g and with a ledge 401h to which the periphery 403b of diaphragm 403 is secured. The cone 403 is coupled via rods 451a with armatures 451b along the exterior of which lie the coils 404. The coils 404 cooperate with the permanent magnets 402 in the posts 401d and are shifted axially as represented by the arrows upon energization of these coils. In this case no special voice coil is necessary since the diaphragm vibrates at the sonic frequency as a result of the sonic frequency electrical signal applied via the coils 404. The armatures 451b are held in place in an angular membering 451c anchored at a central post 451d above a magnet 402a are previously described. The angularly equispaced driving coils can have superimposed on them, together with the sound signal, whatever canting signal may be desired.

In FIG. 6, there is shown a control circuit which may be used for the reproduction of stereophonic music and other audio signals. In this embodiment, three pickup coils are provided and induce or generate a driving potential across the pickup coils which are respectively connected to the drive coil 61-63 with or without intervening modulation or amplification. The amplifiers 141 - 143, shown in FIG. 6, merely represent any of a number of effective amplifier arrangements which may be employed if desired.

In FIG. 7, there is shown a modification in which a horn-type loudspeaker 503, provided with an electroacoustical transducer at 504 is pivotally mounted at 565 so as to swing clockwise or counterclockwise under the control of a gear sector 566 whose teeth 566a mesh with the teeth 566b at the rear end of the speaker. A motor 567 is coupled with the gear sector 566 to rotate same.

In FIG. 8, there is shown a system which makes use of some of the principles previously described. In this embodiment, there is provided a speaker 601 and a speaker 701, the former being of the dynamic type and having an oscillatory and cantilever sound-emitting cone 603 whose normal axis is shown at A in FIG. 8. The member 603 is, for the sake of clarity in this diaphragm, shown to be suspended between a pair of restoring springs 670 and to cooperate with a voice or sound introduction coil 671. The latter may be energized by a switch 672 from a conventional amplifier 673 and the terminal 674. The coils 604 are mechanically connected to the speaker cones 603 as represented by the dot-dash lines, may be energized by any of three systems as set out below.

When switch 672 is open, switch 772 is closed, the switch 772 connecting the amplifier 673 with the speaker 701 whose voice coil is represented at 704 and whose swingable horn 703 is driven by a motor 704a. The motor 704a has a pair of oppositely effective coils which are energized when switches 772 and 672 are respectively closed and opened. When switch 675 is closed, it connects an adjustable AC source 677 to the coil 604 or the coil 704, depending upon which of the ganged switches 678, 679, 680 and 681 are open or closed. These switches may also be ganged when only one-speaker operation is desired. Source 677 applies a low-frequency periodic shift of the axis of the loudspeakers.

An amplitude-sensitive circuit as shown at 690 in FIG. 8 and as described in greater detail in connection with FIG. 5, may be brought into play when switch 691 is closed and switches 75 and 692 are open. Another circuit which may be used with the present invention is that illustrated in a block diagram at 695. In this modification, the amplified output signal (from amplifier 673) is fed via switch 692 to a pair of filters such as the high pass and low pass filters shown at 696 and 697 respectively. In this arrangement, the cone swings in response to frequency rather than amplitude.

The system described above is an improved loudspeaker arrangement which achieves a stereophonic effect with a single speaker unit.

The improvement described and illustrated is believed to admit of many modifications within the ability of persons skilled in the art, all such modifications being considered within the spirit and scope of the invention except as limited by the appended claims.

I claim:

10. 1. A loudspeaker system comprising electroacoustical transducer means including a housing and at least one sound-generating coil in said housing energizable with an electrical signal to produce acoustical vibrations, and means including a cone vibrated by said coil for propagating said acoustical vibrations along the axis of said cone, said coil being anchored at one end to said housing; and a mechanism including an oscillation-producing coil in said housing in addition to said sound-generating coil for oscillating said cone relative to said housing without displacement of said housing whereby the sound-propagating axis is swung out of a normal position during the course of sound transmission by the loudspeaker.
15. 2. A loudspeaker system comprising electroacoustical transducer means energizable with an electrical signal to produce acoustical vibration, and means for propagating said acoustical vibration in a predetermined direction; and an arrangement for oscillating said means whereby the sound-propagating axis is swung out of a normal position during the course of sound transmission by the loudspeaker, said transducer means including a sound-generating coil energizable with said electrical signal to produce said acoustical vibration, a plurality of electromagnetic coils independent of said sound-generating coil and angularly equispaced about the axis of propagation of the system and armature means axially displaceable by said electromagnetic coils and operatively connected with said means for propagating said acoustical vibration.
20. 3. The system defined in claim 2 wherein said means for propagating said vibrations is a diaphragm cone, said armature being affixed to said cone.
25. 4. A loudspeaker system comprising electroacoustical transducer means including sound-generating coil means energizable with an electrical signal to produce acoustical vibration, and means for propagating said acoustical vibrations in a predetermined direction; an arrangement for oscillating said means whereby the sound-propagating axis is swung out of a normal position during the course of sound transmission by the loudspeaker; and a housing enclosing said electroacoustical transducer means, said arrangement including electromagnetic coil means for oscillating said means for propagating said acoustical vibrations without shifting of said housing, said electromagnetic coil means being independent of said sound-generating coil means.
30. 5. The system defined in claim 4, further comprising circuit means for applying a periodic current to said arrangement for oscillating said means at the frequency of said periodic current.
35. 6. The system defined in claim 4, further comprising circuit means for energizing said arrangement to oscillate said means for propagating said acoustical vibrations in accordance with at least one parameter of said electrical signal.
40. 7. A loudspeaker system comprising electroacoustical transducer means energizable with an electrical signal to produce acoustical vibration; means for propagating said acoustical vibrations in a predetermined direction; an arrangement for oscillating said means whereby the sound-propagating axis is swung out of a normal position during the course of sound transmission by the loudspeaker; a housing formed with an iron yoke and a frustoconical housing portion extending from said yoke; at least one permanent magnet mounted in said yoke and forming part of said transducer means; a voice coil received in said yoke and cooperating with said permanent magnet, said means for propagating said acoustical vibrations including a diaphragm cone anchored to said voice coil and formed with an accordion-pleated peripherally affixed to said
45. 65. 70. 75.

housing portion; and an array of angularly equispaced direction-changing coils received in said yoke and provided with respective armatures coupled with said diaphragm for deflecting the axis thereof out of its normal position, not all of said direction-changing coils being energized simultaneously.

8. A loudspeaker system comprising electroacoustical transducer means energizable with an electrical signal to produce acoustical vibration; means for propagating said acoustical vibrations in a predetermined direction; an arrangement for oscillating said means whereby the sound-propagating axis is swung out of a normal position during the course of sound transmission by the loudspeaker; a housing having a yoke and a rigid housing portion of frustoconical configuration extending outwardly from said yoke; an angularly equispaced array of direction-changing coils received in said yoke and each having an armature; and a diaphragm forming said means for propagating said acoustical vibrations and connected to said armatures for displacement thereby, not all of said direction-changing coils being energized simultaneously.

9. The system defined in claim 4 wherein said arrangement is so constructed as to permit an angle of the propagation axis of the sound between 30° and 40° with the normal axis position.

10. A loudspeaker system comprising electroacoustic transducer means energizable with an electrical signal to produce acoustical vibration; directing means including at least one coil for propagating said acoustical vibration in a predetermined direction; and an arrangement coupled with said directing means for controlledly varying the direction of said acoustic vibration with the axis of said propagation shifted from a normal position during the course of sound transmission by the loudspeaker, said arrangement including direction-control means with another coil in addition to said one coil, said direction-control means being coupled with said directing means for oscillating said axis of sound propagation in a single plane past said normal position in a direction generally orthogonal to said predetermined direction and with an am-

plitude as a function of a parameter of said electrical signal.

11. A loudspeaker system comprising electroacoustic transducer means energizable with an electrical signal to produce acoustical vibration; direction means for propagating said acoustical vibration in a predetermined direction; and an arrangement coupled with said directing means for controlledly varying the direction of said acoustic vibration with the axis of such propagation shifted from a normal position during the course of sound transmission by the loudspeaker, said arrangement including direction-control means coupled with said directing means for oscillating said axis of sound propagation past said normal position in a direction generally orthogonal to said predetermined direction and with an amplitude as a function of a parameter of said electrical signal, 15 second direction-control means coupled with said directing means for oscillating said axis of sound propagation past said normal position and in a second direction generally orthogonal both to said predetermined and first directions, and actuator means for actuating said first and second 20 direction-control means whereby the pattern of sound propagation follows a given trajectory related to the characteristics of said acoustic vibration.

12. A loudspeaker system comprising electroacoustic transducer means energizable with an electrical signal to produce acoustical vibration; directing means for propagating said acoustical vibration in a predetermined range of direction; and an arrangement coupled with said directing means for controlledly varying the direction of said acoustical vibration with the axis of sound propagation shifted generally randomly 25 within said range during the course of sound transmission by said loudspeaker, said arrangement including a plurality of direction-control means selectively actuatable by the respective actuation signals to selectively shift and sweep the axis of sound propagation in accordance therewith.

13. A loudspeaker system as defined in claim 12 wherein said actuation signals are derived at least in part from a parameter of said electrical signal. * * * *
